UNITED STATES PATENT OFFICE

120,529

DESIGN FOR A CASING FOR A CHECK WRITING MACHINE OR SIMILAR ARTICLE

Walter B. Payne, Rochester, and Henry Dreyfuss,
New York, N. Y.

Application March 8, 1940, Serial No. 90,774

Term of patent 14 years

To all whom it may concern:

Be it known that we, Walter B. Payne, a citizen of the United States, residing at the city of Rochester, in the county of Monroe and State of New York, and Henry Dreyfuss, a citizen of the United States, residing at the city of New York, in the county of New York and State of New York, have invented a new, original, and ornamental Design for a Casing for a Check Writing Machine or Similar Article, of which the following is a specification, reference being had to the accompanying drawings, forming a part thereof.

Fig. 1 of the drawings is a perspective side view of a casing for a check writing machine embodying our design.

Fig. 2 is a side elevational view showing the design of the casing from the opposite side;

Fig. 3 is a plan view of the casing, and

Fig. 4 is a front elevational view of the casing showing our design.

The essential features of our design for a casing for a check writing machine or similar article are shown by full lines in the drawings.

We claim:

The ornamental design for a casing for a check writing machine or similar article, substantially as shown and described.

WALTER B. PAYNE.
HENRY DREYFUSS.
